RELIEF VALVE FOR STEAM RADIATORS

Harry J. Monteverde, Maspeth, N. Y.

Application September 22, 1948, Serial No. 50,503

5 Claims. (Cl. 137—122)

1

This invention relates to new and useful improvements in air vent valves for steam radiators, and, more particularly, the aim is to provide a novel and valuable valve for the purpose stated and characterized by an improved simplicity of construction, a considerable decrease in size as compared with practicably employable valves of the kinds previously proposed, the total elimination of freely floatable or otherwise wholly loose parts, and the inclusion of a venting means which is essentially rugged and capable of long life without attention; which venting means, acting automatically to open the valve for silently clearing the radiator of trapped air and to close the valve to hold in the radiator the steam supplied thereto, is easily and quickly adjustable by even the ordinary householder and entirely from the exterior of the valve.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 illustrates a pair of adjoining sections of a radiator, with a now favored embodiment of the invention attached thereto at an end section thereof.

Fig. 2 is a view showing said valve on an enlarged scale, and, as seen in Fig. 1, but with the valve casing partially broken away.

Fig. 3 is an end elevation of said valve, looking toward the right in Fig. 3; and at this point it may be stated that Figs. 2 and 3 show the valve drawn substantially to actual scale.

Fig. 4 is a view similar to Fig. 3, but drawn to a scale about twice that of Figs. 2 and 3, and with some components of the venting means indicated in broken lines.

Fig. 5 is a diametral section, taken on the line 5—5 of Fig. 4.

Fig. 6 is an exploded perspective view of various components of the venting means.

Fig. 7 is a detail view, for better illustrating one of said components; this view being a section taken on the line 7—7 of Fig. 6.

The new valve, generally designated 10, is operative in the manner and with the advantages above set forth, when shaped as shown and when including a casing of a diameter of only about 1½" and of about like length. As is well known, the presently most favored valve is of about that diameter but of a length of almost 4".

2

Said casing incorporates a main cup shell 11 closed at its bottom by an inwardly dished bottom wall 12. To facilitate mounting the valve member including portion of the venting means to be described in a moment, the shell 11, having a cylindrical side wall desirably fluted as indicated at 14, has its top wall 15 provided by a separate member shown as in the form of an outwardly dished cap having an integral skirt 16 for suitable securing, as by a threaded connection or otherwise, to the top of the shell 11.

Since the valve of the present invention is adapted for attachment to a radiator 17, in the ordinary manner and by way of the familiar horizontally extended drilled and tapped hole in an end section of the radiator 17, and since the valve 10 as shown herein is arranged to carry, axially extended from its bottom wall and suitably rigidly secured to the latter, a nipple 18 externally threaded to match the internal thread in said hole, thus to dispose the valve 10 as shown in Fig. 1, from now on the walls 12 and 15 of the valve casing will be referred to, respectively, as the inner and outer end walls of the valve.

The forward end of said nipple 18 where the same is flanged to aid in its tight attachment to the inner end wall 12 communicates with the interior of the valve's casing by way of an opening 19 in the inner end wall 12.

For escape of trapped air from the valve at its outer end wall 15, this wall is provided with a suitable plurality, as, for example, three orifices 20. For closing all of said orifices, or opening all of them to a like amount, and similarly to open them to various extents according to conditions, there is swingably mounted on the inner side of the outer end wall 15 the valve member 21 of the venting means.

The valve member 21 is a metal stamping having a main body generally U-shaped in side elevation, and comprising a large upper plate 22 and a lower, somewhat smaller, plate 23, integrally joined to said upper plate by a reduced connector portion 24. This valve member 21, by means of a pair of curled ears 25 integral with said member and a pivot pin 26, also engaged by a pair of curled ears 27 on a plate-bracket 28 suitably secured to the inner side of the outer end wall 15, is swingably carried by said wall for rotation about the axis of the pin 26.

The upper plate 22 of the valve member 21 is provided with three upstruck teats 29, these for entering the orifices 20 to seal the valve against escape of steam from the radiator when the valve

parts are arranged as in Fig. 5. The said parts automatically become thus disposed when the radiator is supplied with steam, due to the pressure of such steam against the side of the plate 22 remote from the outer end wall 15 of the casing.

When, however, the radiator has no or little steam therein and air is trapped in the radiator, the valve member 21 is urged by a light extensible coil spring 30 to swing in a counter-clockwise direction in Fig. 5 about the pin 26, thereby to withdraw the teats 29 from the orifices 20 and thus allow venting of the radiator, as incidental to the admission of steam thereto.

For adjusting the tension of the spring 30, the same is secured in position between a stud-like teat 31 upstruck from the plate 23 of the valve member 21 and a collar 32 integral with and at the inner end of the threaded shank 33 of a screw 34; said screw also integrally carrying at its extreme inner end a reduced portion 35 for coacting with the teat 31 in maintaining the spring 30 in place.

For manual adjustment of the screw 34 the same at the outer end thereof has an enlarged head 36; such head shown as knurled, although if desired the outer end of the screw may be merely kerfed or otherwise shaped for being engaged and turned by a screw driver or other appropriate hand tool. With the screw 34 provided with the head 36 as shown of greater diameter than the threaded shank 33 of the screw, said head is preferably a separate part as illustrated, to aid in ready assembly of the valve member 22 and its associated elements. By way of example, the head 36 is illustrated as threadedly connected to a reduced outer threaded extension from the threaded shank 33 of the screw, and for being wrench-jammed tight on said shank.

The outer end wall 15 of the valve casing has struck up therefrom a neck 37, and the latter is internally threaded, for taking the shank 33 of the screw 34; and for accommodation of the screw's collar 32, the plate 22 of the valve member 21 has an opening 38.

The new valve is mechanically a silently operating one, and since the several orifices 20 of fairly large size may be fully opened when much air is in the radiator, there is, following a sudden inrush of steam at high pressure into a radiator more or less filled with air, no hissing during air venting like that which is given off by a radiator air vent valve of the type now generally used and characterized by the inclusion merely of a single minute air escape hole. The new valve, moreover, has no wholly floating or loose parts, the construction throughout is rugged, and the operation is reliable during prolonged use.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a radiator air vent valve having a hollow casing including an end wall formed with a discharge opening, valve means for the discharge opening, comprising a bracket secured to the inner face of the end wall remote from the discharge opening, a valve member within the body and pivotally mounted on said bracket, said valve

member comprising a larger plate and a smaller plate, said larger plate contacting the inner face of the end wall and being of a size to extend over the discharge opening, said smaller plate being integral with the larger plate at the pivoted end of said valve member and having a free end spaced from the adjacent face of said larger plate, and means operating between the end wall and the free end of said smaller plate for pivoting said valve member away from the inner face of the end wall moving said larger plate clear of the discharge opening.

2. In a radiator air vent valve having a hollow casing including an end wall formed with a discharge opening, valve means for the discharge opening, comprising a bracket secured to the inner face of the end wall remote from the discharge opening, a valve member within the body and pivotally mounted on said bracket, said valve member comprising a larger plate and a smaller plate, said larger plate contacting the inner face of the end wall and being of a size to extend over the discharge opening, said smaller plate being integral with the larger plate at the pivoted end of said valve member and having a free end spaced from the adjacent face of said larger plate, means operating between the end wall and the free end of said smaller plate for pivoting said valve member away from the inner face of the end wall moving the larger plate clear of the discharge opening, and a teat pressed from said larger plate in alignment with the discharge opening and into which said teat projects when said larger plate is in contact with the inner face of the end wall.

3. In a radiator air vent valve having a hollow casing including an end wall formed with a discharge opening, valve means for the discharge opening, comprising a bracket secured to the inner face of the end wall remote from the discharge opening, a valve member within the body and pivotally mounted on said bracket, said valve member comprising a larger plate and a smaller plate, said larger plate contacting the inner face of the end wall and being of a size to extend over the discharge opening, said smaller plate being integral with the larger plate at the pivoted end of said valve member and having a free end spaced from the adjacent face of said larger plate, and means operating between the end wall and the free end of said smaller plate for pivoting said valve member away from the inner face of the end wall moving said larger plate clear of the discharge opening, said pivoting means comprising a screw, an internally threaded neck on the end wall in alignment with the free end of said smaller plate and through which said screw threadedly passes, and an expansion spring operating between the inner end of screw and the adjacent face of the free end of said smaller plate.

4. In a radiator air vent valve having a hollow casing including an end wall formed with a discharge opening, valve means for the discharge opening, comprising a bracket secured to the inner face of the end wall remote from the discharge opening, a valve member within the body and pivotally mounted on said bracket, said valve member comprising a larger plate and a smaller plate, said larger plate contacting the inner face of the end wall and being of a size to extend over the discharge opening, said smaller plate being integral with the larger plate at the pivoted end of said valve member and having a free end spaced from the adjacent face of said larger plate, and means operating between the

end wall and the free end of said smaller plate for pivoting said valve member away from the inner face of the end wall moving said larger plate clear of the discharge opening, said pivoting means comprising a screw, an internally threaded neck on the end wall in alignment with the free end of said smaller plate and through which said screw threadedly passes, and an expansion spring operating between the inner end of said screw and the adjacent face of the free end of said smaller plate, said larger plate being formed with a large opening through which the inner end of said screw freely passes so that said valve member may freely pivot.

5. In a radiator air vent valve having a hollow casing including an end wall formed with a discharge opening, valve means for the discharge opening, comprising a bracket secured to the inner face of the end wall remote from the discharge opening, a valve member within the body and pivotally mounted on said bracket, said valve member comprising a larger plate and a smaller plate, said larger plate contacting the inner face of the end wall and being of a size to extend over the discharge opening, said smaller plate being integral with the larger plate at the pivoted end of said valve member and having a free end spaced from the adjacent face of said larger plate,

and means operating between the end wall and the free end of said smaller plate for pivoting said valve member away from the inner face of the end wall moving said larger plate clear of the discharge opening, said pivoting means comprising a screw, an internally threaded neck on the end wall in alignment with the free end of said smaller plate and through which said screw threadedly passes, an expansion spring operating between the inner end of screw and the adjacent face of the free end of said smaller plate, and an enlarged head on the outer end of said screw by which the screw can be advanced and retracted with relation to said neck for controlling the tension of said spring.
